F. W. TIESING.
Magazine Fire-Arm.

No. 222,749.

Patented Dec. 16, 1879.

UNITED STATES PATENT OFFICE.

FRANK W. TIESING, OF NEW HAVEN, CONNECTICUT.

IMPROVEMENT IN MAGAZINE FIRE-ARMS.

Specification forming part of Letters Patent No. 222,749, dated December 16, 1879; application filed March 31, 1879.

To all whom it may concern:

Be it known that I, FRANK W. TIESING, of New Haven, in the county of New Haven and State of Connecticut, have invented a new Improvement in Magazine Fire-Arms; and do I hereby declare the following, when taken in connection with the accompanying drawings and the letters of reference marked thereon, to be a full, clear, and exact description of the same, which said drawings constitute part of this specification, and represent, in—

Figure 1, a sectional side view with the parts in normal condition; Fig. 2, the same view, position of parts as in operation for charging the arm; Fig. 3, section on line *x x*, Fig. 1.

This invention relates to an improvement in that class of magazine fire-arms in which the magazine is arranged below the barrel, and a carrier combined with a longitudinally-moving breech-piece to transfer the cartridge from the magazine to the barrel; and the invention consists in the construction, as hereinafter described, and particularly recited in the claim.

A is the barrel; B, the magazine, of usual form and relative arrangement; C, the breech-piece, arranged to be moved longitudinally, here represented by means of a lever, D, extending down below the frame to form the handle E, which also serves as the trigger-guard.

This arrangement of lever and breech-piece is substantially that known as the Burgess patent of July 16, 1872. Other devices may be employed for moving the breech-piece without departing from the general principle of this invention.

F is the carrier, extending to the rear, and hung upon a pivot, *a*, so that when the forward end is raised, as in Fig. 1, it will be substantially in line with the barrel.

To operate the carrier, an arm, *b*, extends down from the lever D near the point where the lever is pivoted to the breech-piece. This arm works in a mortise or slot through the carrier, as seen in Fig. 3, and in one side of the arm there is a stud, *d*, provided with a spring, the tendency of which is to force the

stud *d* outward. As seen in Figs. 1 and 3, this stud stands in a slot, *e*, in the carrier.

It will be observed that the carrier is up when the breech-piece is fully closed, as in Fig. 1.

When the lever begins to turn downward to open the breech, the stud *d*, working in the slot *e* in the carrier, turns the carrier downward, as seen in Fig. 2, broken lines 3 indicating the position of the breech-piece and lever when the carrier is completely dropped, so that the carrier is completely opened during the first part of the rearward movement of the breech-piece and but a small portion of its full movement; then continuing the movement of the lever to complete the movement of the breech-piece, the stud *d* turns in the slot *e*, so as to present its inclined side to the rear, as in Fig. 2, solid lines; then the still-continued movement of the lever will force the stud *d* inward, so as to pass onto the inner surface of the carrier, and the stud will be held in that position until it arrives at the notch or slot *f*, as seen in broken lines 4, Fig. 2, when the stud will be free to move outward into the said notch *f*.

The result of thus dropping the carrier at the start of the breech-piece rearward is that the cartridge for the magazine will follow the breech-piece and pass onto the carrier without any sudden throw, as is the case in the class of arms in which the cartridge does not pass from the magazine until the breech-piece is fully opened, as in the Burgess arm before referred to, and which sudden movement of the cartridge throws it with great force against the breech-piece, sufficient in the case of long cartridges to sometimes cause explosion, as the primer is liable to come in contact with a projecting part of the breech-piece; but under this improvement the cartridge, following, as it does, the breech-piece, is saved from any such force or difficulty.

When the breech is fully opened and the cartridge in its position on the carrier, the lever is turned backward, which forces the stud *d* against the forward side of the notch *f* in the carrier, causing the carrier to instantly rise to the position seen in Fig. 1, and present

the cartridge forward of the breech-piece. The stud *d*, passing down out of the notch *f*, and below the edge *h* of the carrier, holds the carrier elevated until the stud arrives at the position indicated in broken lines *g*; then the bevel side of the stud lies vertically beneath the slot *e* in the carrier, and in the completion of the movement of the lever is forced by the carrier into its arm until it arrives in line with the slot *e*, as seen in Fig. 1; then it flies outward into the slot *e*. The cartridge in this movement is forced to the barrel and the breech-piece completely locked.

Another great advantage of this improvement arises from the fact that the carrier cannot be raised or moved at all unless the breech-piece be completely opened, the connection for raising the carrier being made instantaneously, and not during a part of the movement of the breech-piece, as in previous constructions; hence, if the breech-piece be not completely opened, this engagement will not take place, and the result will be that the cartridge on the carrier will be returned to the magazine from whence it came, and the shell on the face of the breech-piece, held by the extractor, will be returned to the barrel, it being understood that in nearly all of this class of arms the ejection of the shell occurs on the completion of the rear movement of the breech-piece.

In the arm as usually constructed, where the ejection fails and the carrier is moved upward the arm is clogged because of the cartridge below and the shell above coming together.

Other advantages of this peculiar movement of the breech-piece—that is to say, so as to allow a cartridge from the magazine to follow the breech-piece—will be apparent to those skilled in the art without being particularly pointed out in this specification.

The connection between the breech-piece and the carrier (here shown to produce this peculiar movement) is sufficient to enable those skilled in the art to adapt this invention to arms in which the breech-piece is moved by devices differing from the lever herein mentioned, and also that, if preferred, the carrier may be hung at a lower point, so as to present the cartridge in front of the breech-piece inclined to the line of the barrel.

As an illustration of such adaptation to what are commonly called "bolt-guns," I show a sec-

tional view in Fig. 4, in which the barrel and magazine are the same as in Figs. 1 and 2. *D'* is the bolt or breech-piece, arranged to be moved longitudinally to and from the barrel, as in bolt-guns generally. *E'* is the carrier, hung at the rear and so as to lie in an inclined position when elevated. *F'* is a lever, hung beneath the carrier, as at *f'*, and extending up into the path of two dogs, *s* and *t*, on the breech-piece. The dog *s* extends forward from its pivot *s'*, and the dog *t* rearward from its pivot *t'*, the tails of the two dogs toward the center, and rest on a spring, *u*, the tendency of which is to hold the nose of each dog downward, but yet yield to allow the nose to rise when upward force is applied thereto. Under this arrangement, when the breech-piece begins its rearward or opening movement the dog *t* strikes upon the end of the lever *F'* and turns it backward. On the lever *F'* is a stud, *w*, which lies within a slot, *x*, in the carrier, and which communicates the movement of the lever to the carrier and turns the carrier down during the first part of the rearward movement of the breech-piece, and as soon as the carrier has been thus dropped the dog *t* escapes from and passes over the lever *F'*. The breech-piece continuing its rear movement, the dog *s* passes over the end of the lever until its nose drops in rear of said lever, as indicated in broken lines; then, when the breech-piece is returned, the dog *s* returns the lever *F'*, and consequently raises the carrier at the beginning of the forward movement of the breech-piece.

It will be readily seen that the movement of the carrier relative to the movement of the breech-piece is the same as that first described.

I claim—

The combination, in a magazine fire-arm, of a carrier arranged to transfer the cartridge from the magazine to a position in front of the open breech-piece, and a lever hinged to the said breech-piece, with an arm extending downward from said lever, and mechanism, substantially such as described, to automatically engage and disengage said arm with or from the carrier, substantially as and for the purpose specified.

FRANK W. TIESING.
